UNITED STATES PATENT OFFICE.

CHARLES W. DUNHAM, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

GRADE-CROSSING SIGNAL.

1,330,064.

Specification of Letters Patent. Patented Feb. 10, 1920.

Application filed April 24, 1917. Serial No. 164,111.

To all whom it may concern:

Be it known that I, CHARLES W. DUNHAM, a citizen of the United States, residing at Edgewood Borough, in the county of Allegheny and State of Pennsylvania, have invented certain new and useful Improvements in Grade-Crossing Signals, of which the following is a specification.

My invention relates to warning signals for intersections of highways and railways.

I will describe one form of signal and one controlling means for such signal, each embodying my invention, and will then point out the novel features thereof in claims.

In the accompanying drawings, Figure 1 is a view showing one form of signal embodying my invention located at the intersection of a railway and highway. Fig. 2 is a view showing in front elevation the actuating mechanism for the signal shown in Fig. 1, the mechanism being removed from the casing C and partly shown in section. Fig. 3 is a view showing in side elevation the mechanism shown in Fig. 2. Fig. 4 is a diagrammatical view showing one form of controlling apparatus embodying my invention.

Similar reference characters refer to similar parts in each of the views.

Referring to the drawings in detail and particularly to Fig. 1, I have here shown a warning signal S embodying my invention, which signal is located adjacent the intersection of a railway T and a highway H. The signal comprises, in this instance, a post or standard 9 upon the upper end of which is mounted a casing C containing the operating mechanism for a semaphore D. The semaphore D is of the pendulum type, that is, a semaphore which is caused to oscillate to give a danger indication, thereby warning persons crossing the railway track of an approaching train or car. The semaphore as here shown comprises a rod 10 and a bob 11, the bob consisting of a disk 12 colored preferably red and having imprinted upon the opposite sides thereof the word "Stop".

As shown in Fig. 1, the semaphore D is pivotally mounted at point 10^a upon the outer end of a tubular arm 14 secured to casing C, the arm being supported in horizontal position by means of a brace rod 15. The semaphore D is adapted to be swung to and fro by means of the operating mecha-

nism through the medium of a connecting rod 16 arranged within the tubular arm 14. A pair of spaced shields 17 are secured to the brace rod 15, their outer sides having the words "Look" and "Listen" imprinted thereon. By means of a latching device located within the casing C, the semaphore D may be latched in the inclined position, as shown in Fig. 1, in which position the shields 17 conceal the disk 12. For the purpose of giving a danger indication at night, the disk 11 of the semaphore is provided with an electric lamp 13. This lamp, as hereinafter explained, is so controlled that it is illuminated only when the semaphore is unlatched.

I will now describe the mechanism for oscillating the semaphore D, reference being had to Figs. 2 and 3. F designates a sectional supporting frame suitably secured within the casing C and comprising front and rear sections f' and f respectively, spaced apart by means of bolts, as shown. The rear side of the rear section f is formed with a horizontal shelf 18 upon which are mounted two electromagnets m and m'. These magnets are disposed at opposite sides of a horizontal shaft 19, the latter being journaled in suitable bearings formed in the frame F. The upper ends of the electromagnets are formed with pole pieces 20 and 20^a, while loosely mounted on the shaft 19 and arranged upon opposite sides thereof are armatures 21 and 21^a, which are adapted to be operated by their corresponding electromagnets m or m', as will be understood. Oscillatory motion is imparted to the shaft 19 by means of the electromagnets and the armatures 21 and 21^a through the medium of laterally extending arms 22 and 22^a fixed to the shaft 19. (See also Fig. 4.) By means of a circuit controller to be fully described hereinafter, electromagnets m and m' are alternately energized to alternately move the armatures 21 and 21^a downwardly, and during such movement the armatures are caused to alternately engage the arms 22 and 22^a, whereby oscillatory motion is transmitted to the shaft 19. By virtue of this oscillatory movement of the shaft 19, an operating crank 23 fixed to the shaft between the sections f and f' of the frame F is caused to oscillate, which in turn swings the semaphore D to and fro through the medium of

the connecting rod 16. A weight 24 is fixed to the shaft 19 between the sections of the frame F for the purpose of balancing the crank 23, as will be understood.

5 With the parts of the mechanism proportioned as shown in Figs. 2 and 3, when the semaphore is in the vertical position each armature 21, 21^a is spaced about 5° from the pole pieces of the corresponding magnet, and 10 each armature is resting on its corresponding arm 22 or 22^a. As the semaphore swings to the right from the vertical position, armature 21 reaches pole pieces 20 when the semaphore is about 5° from the vertical position, 15 and during the remainder of the stroke arm 22 swings away from this armature while arm 22^a raises armature 21^a. The operation of armature 21^a when the semaphore swings to the left from its vertical position 20 is similar.

I will now describe the circuit controller for alternately energizing the electromagnets *m* and *m'* to cause oscillatory movement of the semaphore D, as just described. Referring to Figs. 2, 3 and 4, the circuit controller is indicated generally at K, and as here shown, comprises a terminal board 25 secured to the end of the frame F and upon which are mounted a spring contact finger 26 and two spring contacts 27 and 27^a, the spring contact finger being interposed between the spring contacts and biased by means of its own tension to normally engage the contact 27. Pivoted on 30 the frame F at 28 is an arm 29, the upper end of which carries a block 30, formed of insulating material, which is provided with a slot 31 to receive the lower end of the contact finger 26. The lower end of arm 29 is 35 bifurcated and carries a pin 29^a on which two rollers 32 and 32^a are free to revolve. The outer end of the shaft 19 is provided with a sector cam 33 fixed to the shaft for movement therewith, the curved edge of 40 which is formed with four cam surfaces *a*, *b*, *c* and *a'*, such surfaces being adapted to successively engage the roller 32 when the cam is oscillated. It will be noted that the cam surfaces *a*, *b* and *c* are each disposed at a 45 different radius, taking the shaft 19 as a center, and that the radius of surface *a'* is the same as that of surface *a*. 34 designates a pivoted cam, the free end of which is disposed at substantially the same radius as the 50 cam surface *c*. The cam 34 is biased in a clockwise direction by means of springs 35 and 35^a carried by cam 33, the upward movement of the cam being limited by a stop 36 carried by the cam 33. This cam 34 cooperates with roller 32^a.

As previously stated, the semaphore D is adapted to be latched in an inclined position by means of a latching device, which I will now describe. Referring to Figs. 2 and 3, 65 the latching device is designated generally

at L, and as here shown comprises an actuating electromagnet M² secured to the frame F between the sections *f* and *f'* at a point below the crank 23. The magnet M² actuates an armature 42 mounted on an arm 43, the latter having its lower end bifurcated and pivotally mounted on a pin 44. The armature 42 is biased toward the pole pieces of the magnet M² by means of a counterweight 45^a fulcrumed upon the pin 44 in the bifurcation at the end of the arm. This counterweight is carried on a bent lever 45, the portion of which above the pivotal point 44 rests against a projection 43^b on the arm 43. The armature 42 is not, however, biased into 8 actual contact with the poles of the magnet M² but to a position slightly spaced from the poles. This is due to the fact that the clockwise movement of the lever 45 is limited by means of a stop screw 45^b carried by the 15 lever and passing through a slot 43^a in arm 43. When this screw is properly adjusted the lever will move the armature to the previously mentioned spaced position and no farther, as the screw 45^b will then engage the 20 frame of the magnet as shown in Fig. 2. The reason for thus biasing the armature to a position in spaced relation to the pole-pieces of the magnet will appear hereinafter. Pivotedly connected to the medial portion 25 of the armature 42 by a pin 46^a are a pair of spaced links 46, 46, the upper ends of which carry a pin 70. Pivotally mounted on this pin are two other spaced links 71, 71^a, the other ends of 30 which are pivoted on a pin 48 which is mounted in frame F. Also pivotally mounted on the pin 70 is a locking dog 47, the free end of which is forked to straddle the fixed pin 48. The upper arm of the forked end 105 of the dog 47 is beveled to provide a tooth 49, which when the dog is elevated to the position shown, is adapted to engage a rack bar 50 carried by the operating crank 23. The dog 47 is elevated by the armature 42 when 110 the latter is attracted by the magnet M², through the medium of a leaf spring 51 which is pivotedly mounted upon the armature 42 by means of a bracket 52. A yoke 53 and a pin 54 confine the spring 51 between 115 the links 46, 46, such spring having its upper end engaging a lug 55 formed on the dog 47. A screw 56 adjustably mounted on the armature 42 is arranged for engagement with the spring 51 when the armature is in attracted position, but not when the armature is released.

The operation of the latching device is as follows: When magnet M² is energized, armature 42 is closed against the pole pieces of this magnet so that screw 56 presses against the leaf spring 51. The upper end of this spring then presses against the lug 55 on dog 47, so that this dog is swung upwardly to such position that its tooth 125 130

engages one of the teeth on rack bar 50, thereby latching the semaphore in its extreme left hand position against the action of gravity on the semaphore. This is the 5 condition in which the parts are shown in Figs. 2 and 3. If, now, magnet M^2 becomes deenergized, armature 42 will be released and will swing out, thus allowing the links 46 to swing outwardly and down- 10 wardly under the influence of the force exerted on dog 47 by rack bar 50. The dog will then swing down around tooth 49 as a center until this tooth is out of the path of rack bar 50, but the forked end of the dog 15 will be kept astraddle of pin 48 owing to links 71, 71^a. The semaphore is then free to swing under the influence of gravity and of magnets m and m' . As soon as the semaphore is thus released, however, counter- 20 weight 45^a will return the armature 42 to nearly its closed position, so that dog 47 will be returned nearly to its latching position. Screw 56 does not exert any pressure on 25 spring 51 at such time, however, hence the dog will rest with the upper arm of its forked end lying on pin 48, and in this position the tooth on the dog will be just out of the path of the teeth on rack bar 50. If, then, magnet M^2 becomes energized, the clos- 30 ing of armature 42 will cause screw 56 to exert pressure on spring 51, and the upper end of this spring will then swing dog 47 upwardly so that its tooth 49 will engage with one of the teeth on rack bar 50 the 35 next time the semaphore swings to its extreme left-hand position. The semaphore will consequently be caught and held in this position.

It will thus be seen that when the magnet M^2 is deenergized, armature 42 is held in nearly its closed position and the dog is held in nearly its latching position, so that only a small amount of pull on the armature is required to move the parts into active or 45 latching position. This construction, therefore, makes it possible to use a small controlling magnet and a comparatively small amount of current to energize the magnet.

The operation of the signal will be de- 50 scribed in connection with the controlling means for such signal shown in Fig. 4. Referring to Fig. 4, I have here shown diagrammatically the signal S, one arrangement of circuits therefor, and one means for 55 automatically controlling such circuits. T designates a stretch of railway track as in Fig. 1. The rails of the stretch are divided to form a track section by means of insulated joints 57, 57. Although I have shown 60 only one of such sections, it is to be understood that a plurality of sections may be employed for controlling the signal S by means of interlocking relays, as will be understood by those versed in the art. The 65 track section here shown is provided with a

track circuit including a battery B' connected across the track rails at one end of the section and a relay R bridging the track rails at the other end of such section. Relay R is provided with two contact fingers 70 58 and 59, respectively. Contact finger 58 controls the supply of current to the lamp 13 from a battery B through a lower contact 58^a, while contact finger 59 controls the supply of current to magnet M^2 from battery B through an upper contact 59^a. From this arrangement it will be seen that when the relay is energized contact finger 58 disrupts the lamp circuit, while contact finger 59 completes the circuit for the magnet M^2 . 75 80 When the relay is deenergized the reverse operation of the contact fingers occurs to complete the lamp circuit and to disrupt the circuit for the magnet M^2 , as will be understood. The circuits for the lamp 13 and the magnet M^2 are thought to be obvious, and therefore the same will not be traced. 85 As shown in Fig. 4, magnets m and m' are supplied with current from a battery B, the circuit for magnet m' being from battery B, 90 through wires 60, 40 and 39, windings of magnet m' , wire 38, contact 27^a, contact finger 26, and common return wire 37 back to battery. The circuit for magnet m is from battery B, wires 40 and 39, magnet m , wire 95 41, contact 27—26, back to battery. Although the lamp 13 and the magnet M^2 are supplied with current from the same source as the magnets m and m' , it will be noted that the magnets m and m' are controlled 100 independently of the relay R and its contact fingers.

The operation of the signal is as follows: With the parts in the normal positions, as shown in Fig. 4, let it be assumed that a 105 train or car enters the track section. Relay R is immediately deenergized to release the latching device L and illuminate the lamp 13.

With the latching device released, the 110 semaphore D starts to swing from its latched position, which movement causes cam 33 to be moved in a clockwise direction. Soon after this movement begins, cam surface b moves to such position that it is opposite roller 32, and inasmuch as contact finger 26 is biased to close against contact 27, arm 29 then swings in counter-clockwise direction so that contact 26—27 closes. 115 Magnet m then becomes energized to attract 12 its armature and so to transmit a force to crank 28 which force assists the action of gravity tending to swing semaphore D to the right. As the movement continues, cam 34 is engaged by roller 32^a and caused to 125 swing with relation to cam 33, in opposition to the action of springs 35 and 35^a. After the entire surface b has traversed roller 32, this roller rides outwardly on inclined surface b' until roller 32^a reaches the 13

upper corner 34^a of cam 34. At this point the action of springs 35, 35^a overbalances the biasing force acting an arm 29 so that roller 32^a suddenly snaps around corner 34^a and rests on the cam surface 34^b of cam 34. 5 This sudden movement of roller 32^a swings arm 29 in clockwise direction so that contact finger 26 is swung over into engagement with contact 27^a. When this reversal 10 occurs, semaphore D is 5° beyond the vertical position so that armature 21 has just reached pole pieces 20. Magnet *m* then becomes deenergized and magnet *m'* becomes energized, but this does not materially retard the movement of the semaphore because 15 armature 21^a is then 10° away from the poles of its magnet and so is practically out of the influence of this magnet. Furthermore, the impedance of the coils prevents 20 the magnetic field from reaching a high value during the brief interval in which this magnet is energized. As soon as the snap action just referred to has taken place, cam 34 returns to its initial position under 25 the influence of springs 35, 35^a, but this does not affect the position of arm 29. No change occurs when roller 32^a leaves cam 34 and roller 32 rides onto surface *c*, because the radius of surface *c* and the radius of 30 surface 34^b are the same. As the movement of the semaphore continues, roller 32 rides down onto cam surface *a'*, whereupon arm 29 swings enough to allow contact finger 26 to return to its middle or open position, 35 thus deenergizing magnet *m'*. Soon after this last movement of roller 32 takes place, the semaphore reaches its extreme right-hand position and starts to return under the influence of gravity, whereupon cam 33 40 moves in counter-clockwise direction. After a slight movement, roller 32 rides up onto cam surface *c* and so swings arm 29 to close contact 26—27^a. Magnet *m'* then becomes energized to assist the action of gravity in 45 swinging the semaphore. After surface *c* leaves roller 32, cam 34 co-operates with roller 32^a to hold contact 26—27^a closed, that is, to keep magnet *m'* energized, until the semaphore is 5° beyond its middle position, 50 when cam 34 suddenly releases roller 32^a and so allows roller 32 to drop to cam surface *b*. Magnet *m* then becomes energized for a short time, but is thereafter deenergized when roller 32 reaches cam surface *a* 55 whereupon the contact finger 26 is returned to its middle or open position.

It will be seen from the foregoing that during each swing of the semaphore the magnet which assists in such swing becomes 60 deenergized when the semaphore reaches a point 5° beyond its vertical position. The object of this is to use as little energy as possible by taking advantage of the pendulum principle and obtaining a comparatively large amplitude of swing by the cu-

mulative effect of impulses which individually would not be able to produce such an amplitude. It will be further seen that the reversal of contact finger 26 is always accomplished by a snap action due to the operation of roller 32^a by cam 34. This action avoids the possibility of the semaphore being in such position as to be deprived of motive power, as might occur when the arc of oscillation is very small if the reversal 75 of the contact finger took place slowly.

It will be evident, therefore, that with the latching device released, the semaphore D is swung to and fro continuously, so long as a train remains within the track section, 80 and that such movement of the semaphore gives a warning indication to persons approaching the grade crossing. When the car or train passes out of the track section, the relay R is again energized to extinguish the 85 lamp and to cause the latching device to assume its active position. Then as the semaphore in its swinging movement reaches its extreme position between the shields 17, the latching device engages the crank 23 and 90 thereby locks the semaphore in obscured position, so that the signal again gives a clear or safety indication.

It will be clear that in the event of failure of battery B, the semaphore will be released, 95 and will hang idly in the vertical position, thus indicating that the signal is out of order. Should, however, the latching device become ineffective while the operating magnets remain effective, the semaphore will 100 be released and continuously oscillate, thus giving the warning or "stop" indication.

It is to be understood that the track section to which relay R is connected is located adjacent the grade crossing so that the 105 signal S will be operated before the train or car reaches such crossing.

Although I have herein shown only one form of signal and one controlling means, each embodying my invention, it is understood that various changes and modifications may be made therein within the scope of the appended claims without departing 110 from the spirit and scope of my invention.

Having thus described my invention, what 115 I claim is:

1. A highway crossing signal comprising a semaphore, means for continuously moving said semaphore, latching means for locking said semaphore against movement, a circuit controller operated by said semaphore for controlling said moving means, said circuit controller being capable of assuming two extreme positions to actuate said moving means and an intermediate position to render said moving means inactive, said circuit controller maintaining the intermediate position when the semaphore is in locked 125 position.

2. A highway crossing signal comprising 130

a semaphore, means for continuously moving said semaphore and comprising a pair of electromagnets, means for latching said semaphore in a predetermined position, 5 means for controlling said magnets comprising a contact finger and a cam operable by said semaphore for actuating said finger to alternately energize said magnets when said semaphore is released and to deenergize both of said pairs of magnets when said semaphore is in latched position.

3. A highway crossing signal comprising a pendulum, means for latching said pendulum in an inclined position, means constantly tending to move said pendulum when released and comprising two electromagnets, 15 a contact finger, a cam actuated by said pendulum to move said contact finger to alternately energize said electromagnets to continuously move said pendulum and to deenergize said electromagnets when the pendulum is in latched position, and an electro-responsive device controlling said latching means.

25 4. A highway crossing signal comprising a pendulum semaphore, means for continuously swinging said semaphore, and a latching device for said semaphore, said latching device comprising a member moving with the semaphore, an electromagnet, a dog engageable with said member, and means operable by said electromagnet for moving said dog into and out of engagement with said member, said means comprising an armature 30 biased to a position slightly spaced from the poles of said electromagnet but capable of liberal movement away from said magnet to permit disengagement of said dog from said member.

40 5. A highway crossing signal comprising a pendulum semaphore, means for continuously swinging said semaphore, and a latching device for latching said semaphore in one of its extreme positions, said device comprising an oscillating member biased to a point adjacent one end of its stroke, a dog operable by said member, means for moving said member to the end of its stroke, and resilient means connecting the dog and member for moving said dog into engagement with said semaphore when said member is moved to the end of its stroke.

55 6. A highway crossing signal comprising a pendulum semaphore, means for continuously swinging said semaphore, and a latching device for latching said semaphore in one of its extreme positions, said device comprising a member moving with the semaphore, an electromagnet, a pivoted armature 50 for the electromagnet biased to a point adjacent the poles of said electromagnet, a dog, and means connecting said dog and armature for moving the dog into engagement with said member when said electromagnet is energized.

7. A highway crossing signal comprising a pendulum semaphore, means for continuously swinging said semaphore, and a latching device for latching said semaphore in one of its extreme positions, said device comprising a member moving with the semaphore, an electromagnet, a pivoted armature for the electromagnet biased to a point adjacent the poles of said electromagnet, a dog, and adjustable resilient means connecting 70 said dog and armature for moving the dog into engagement with said member when said electromagnet is energized.

8. A highway crossing signal comprising a pendulum semaphore, means for continuously swinging said semaphore, and a latching device for said semaphore comprising a dog, a pivoted member biased to an intermediate position, and means for moving said member to another position to cause said dog to latch said semaphore, said member being capable of assuming still another position wherein said dog releases the semaphore.

9. A highway crossing signal comprising a pendulum semaphore, means for latching said semaphore in an inclined position, said means comprising a member moving with the semaphore, a dog, an electro-responsive device, mechanism operatively connecting 90 said dog and electro-responsive device for moving said dog into engagement with said member, when said electro-responsive device is energized, the engagement of said dog and said member being such as to allow said dog to be forced out of engagement with said member when the electro-responsive device is deenergized; and biasing means for returning said dog to nearly its engaging 95 position.

10. A latching device for a pendulum semaphore signal, comprising a member moving with the semaphore, a dog, an electromagnet, an armature for said magnet, means interposed between said armature and said dog for holding said dog in engagement with said member to latch the semaphore when the armature is attracted by said magnet and for permitting said dog to move out of the path of said member when the armature moves a considerable distance from the poles of the magnet, and means for biasing 110 said armature to such position that it is nearly closed against the poles of the magnet, in which position the dog is nearly but 115 not quite in position to engage said member.

11. A latching device for a pendulum semaphore signal, comprising a rack bar 50 movable with the semaphore, an electromagnet M^2 , an armature 42 for said magnet 125 pivotally mounted at 44, links 46 pivotally attached to said armature, links 71, 71^a pivotally connected with said links 46 by a pin 70, a fixed pin 48 to which links 71, 71^a are pivotally attached, a dog 47 pivotally mounted 130

- on pin 70 and having a tooth 49 adapted to engage the teeth of rack bar 50, said dog having a part adapted to rest on pin 48, whereby when the armature swings away from the magnet poles, the dog may swing to such position that its tooth 49 is out of the path of rack bar 50, a counterweight 45^a for biasing armature 42 to nearly its closed position wherein the upper arm of the bifurcated end of dog 47 rests on pin 48 and tooth 49 is out of the path of rack bar 50, a leaf spring 51 pivotally attached to armature 42 and coöperating with a lug 55 on dog 47, and a member 56 attached to the armature for exerting pressure on the leaf spring when the armature is closed and for thereby swinging dog 47 into the path of rack bar 50.

12. A signal comprising a pendulum semaphore, two electromagnets for swinging said semaphore in opposite directions, a circuit controller for governing said magnets comprising a contact finger capable of a middle position in which both magnets are deenergized and two extreme positions in which one magnet or the other is energized, and means controlled by the semaphore for swinging said contact finger to one extreme position or the other while the semaphore is approaching its middle position from one direction or the other and for holding the contact finger in its middle position while the semaphore is in an extreme position.

13. A signal comprising a pendulum semaphore, a magnet *m* for swinging said semaphore toward the right and a magnet *m'* for swinging said semaphore toward the left, means for latching said semaphore in one extreme position of its stroke, means including a contact finger 26 for energizing one magnet or the other according as the finger is moved to one extreme position or the other; and means controlled by said semaphore for moving said finger to energize magnet *m* while the semaphore is approaching its middle position from the left, for moving said finger to energize magnet *m'* while the semaphore is approaching its middle position from the right, and for holding said finger in an intermediate position wherein both magnets are deenergized while the semaphore is in said extreme position.

14. A signal comprising a pendulum semaphore, a magnet *m* for swinging said semaphore toward the right and a magnet *m'* for swinging said semaphore toward the left, means for latching said semaphore in one extreme position of its stroke, means including a contact finger 26 for energizing magnet *m* or magnet *m'* according as such finger engages a fixed contact 27 or 27^a and for deenergizing both magnets when such finger is out of engagement with both of said con-

tacts; and means controlled by said semaphore for moving said finger 26 into engagement with contact 27 when the semaphore is swinging toward the right, for moving said finger into engagement with contact 27^a when the semaphore is swinging toward the left, and for holding said finger out of engagement with either contact while the semaphore is in said extreme position.

15. A signal comprising a pendulum semaphore, two magnets *m* and *m'* for swinging said semaphore to the right and left respectively, means including a contact finger 26 for energizing magnet *m* or *m'* according as such finger is moved into engagement with a fixed contact 27 or 27^a, a cam 33 moving with the semaphore and having four cam surfaces *a*, *b*, *c*, and *a'*; a cam follower coöperating with said surfaces for permitting said finger to move into engagement with contact 27 while the follower rests on surface *b*, for shifting said finger into engagement with contact 27^a when the follower rests on surface *c*, and for holding said finger out of engagement with both contacts when the follower rests on surface *a* or *a'*; said cam surfaces being so arranged that the follower rests on surface *a* or *a'* while the semaphore is in one extreme position or the other and that surface *b* is opposite the follower while the semaphore is approaching its middle position, and a second cam 34 for holding said contact finger in engagement with contact 27^a while the semaphore is approaching its middle position from the right.

16. A signal comprising a pendulum semaphore, two magnets *m* and *m'* for swinging said semaphore to the right and left respectively, means including a contact finger 26 for energizing magnet *m* or *m'* according as such finger is moved into engagement with a fixed contact 27 or 27^a, a cam 33 moving with the semaphore and having two cam surfaces *b* and *c*, a cam follower coöperating with said surfaces for permitting said finger to engage contact 27 when the follower rests on surface *b* and for shifting the finger into engagement with contact 27^a when the follower rests on surface *c*, said cam surfaces being so arranged that surface *b* is opposite the follower while the semaphore is approaching its middle position, and a second cam 34 for holding finger 26 in engagement with contact 27^a while the semaphore is approaching its middle position from the right and until the semaphore has passed beyond such middle position.

In testimony whereof I affix my signature in presence of two witnesses.

CHARLES W. DUNHAM.
